ELECTRICAL CONDENSER

Hermann Sträß, Stuttgart, Germany, assignor to
 Robert Bosch Gesellschaft mit beschränkter
 Haftung, Stuttgart, Germany

Application July 27, 1937, Serial No. 156,023
 In Germany August 5, 1936

6 Claims. (Cl. 175—41)

The invention relates to improvements in flat pack or pressed electrostatic wound condensers, particularly to those having a very thin metal coating (smaller than 0.002 millimetre or 0.001 mm. and particularly those whose coating is of the order of 0.0001 millimetre thick) in which the current connection is made on the front sides of the condenser.

It is known to arrange current connections of wound condensers at the front sides of the condenser in such a way that the metal coating of the condenser is allowed to project up to the front of the wound condenser or beyond it and a metal layer is applied to the front, for instance, by spraying by the Schoop spraying process. A connecting wire can be soldered on to this metal layer. In order to obtain a good adhesion of the current connecting layer on to the metal coating of the condenser, it is useful to apply the current connection layers before impregnating the wound condenser. In order that after applying the metal layer, the impregnating medium may penetrate into the condenser, it is advantageous not to provide the whole front of the condenser with a metal layer, but only one or several parts of its front side.

Now it has been discovered that a flat pressed wound condenser the current connections of which are produced in the manner indicated may under certain circumstances have a greatly reduced puncture strength when the metal layer is applied to those parts of the inner condenser windings that have been bent during pressing. This is explained by the fact that the impregnating agent cannot penetrate into those parts of the front of the condenser to which the metal layer is applied. Therefore the parts of the condenser under the metal layers applied to the front sides are not as fully provided with the impregnating agent as the other parts, since there is a longer way for the impregnating agent to reach these parts than if it could penetrate directly on the front side of the condenser. The parts of the condenser situated under the metal layer have consequently a somewhat smaller puncture strength than the other points.

In order to keep the reduction of the disruptive strength so produced as small as possible, according to this invention the parts of the wound bands bent during the flat pressing of the wound condenser are kept free from the current connection layer at least within the first inner third of the winding bands on the front of the condenser. These bent parts are, of course, considerably stressed by the mechanical tensile

stresses which have occurred during the flat pressing. It is consequently doubly important that these parts should be adequately impregnated.

5 The invention is more particularly described with reference to the accompanying drawing, in which:

Figure 1 is an elevation of one form of construction.

Figure 2 is a corresponding plan view of a flat pressed wound condenser.

The condenser is wound with separate bands. During the flat pressing, especially in the regions indicated by *a* and *b* sharp bent points of the inner winding bands occur, and in their neighbourhood considerably tensile stresses arise. At *c*, *d*, and *f*, metal layers are sprayed on, on to which a current connection wire *g* is soldered. The regions *a* and *b* are left free from the metal layers.

10 The metal layers *c* and *d* are situated on the front faces of the outer condenser windings, and these, on being pressed flat are not so sharply bent as the inner windings. In order to provide a current lead for the inner windings from the front faces of the condenser, a further metal layer *f* is provided between the two bent places *h* and *i* of the innermost winding; this metal layer here covers the front faces of the inner windings 20 which have been left free from the layers *c* and *d* at the bent parts.

15 Instead of the metal layers *c* and *d* being applied at the rounded off parts of the condenser they may also be arranged between the points *h* and *i* and united with the metal layer *f*. However, this arrangement has the disadvantage, that fairly large cohering masses of metal then arise which readily fall off or burst and thus give rise to contact difficulties. Especially in condensers with very thin metal coverings (smaller than 0.002 mm.) it is useful to apply in the region between the two bent points *h* and *i* as small a metal layer as possible.

25 Condensers of this kind with very thin metal coverings have the property that in the event of puncture, the metal covering round the point of puncture disappears in a region which is larger than the hole in the dielectric, whereby the short circuit current is by itself interrupted. In this process there occur very small quantities of gas which cause a slight swelling of the condenser. This swelling occurs particularly in those regions of the wound condenser where the windings lie flat. With this swelling there is a certain possibility that the sprayed-on metal layers will burst.

By the arrangement described this danger is reduced to the lowest possible degree.

I declare that what I claim is:

1. An electric wound condenser of the flat type comprising flat strip windings coiled upon themselves, a dielectric separating the conducting metal coatings of the condenser, said metal coatings of different potential vice versa projecting one on each front side of the condenser and a layer of metal applied on the front sides electrically connected to the projecting edges of the coatings whereby at least the first inner thirds of the bent parts of the windings are kept free from said metal layers.

2. An electric wound condenser of the flat type comprising flat strip windings coiled upon themselves, a dielectric separating the conducting metal coatings of the condenser, said metal coatings of different potential vice versa projecting one on each front side of the condenser and one or more coherent layers of metal applied on the front sides electrically connected to the projecting edges of the coatings whereby at least the first inner thirds of the bent parts of the windings are kept free from said metal layers.

3. An electric wound condenser of the flat type comprising flat strip windings coiled upon themselves, a dielectric separating the conducting metal coatings of the condenser, said metal coatings of different potential vice versa projecting one on each front side of the condenser and one or more coherent layers of metal applied on the front sides electrically connected to the projecting edges of the coatings whereby at least the first inner thirds of the bent parts of the windings are kept free from said metal layers and a metal wire conductor soldered to said applied metal layers, each conductor electrically connecting all of the applied metal layers on each side of said condenser, but being spaced from said windings.

4. An electric wound condenser of the flat type comprising flat strip windings coiled upon themselves, a dielectric separating the conducting metal coatings of the condenser, said metal coat-

ings of different potential vice versa projecting one on each front side of the condenser and at least three coherent layers of metal applied on the front sides electrically connected to the pro-

5 jecting edges of the coatings whereby the contact metal layers of the inner windings of the condenser are applied between the two bending points of the innermost winding and those of the outer windings on one or on each rounded
10 part of the front sides of the condenser, the inner bent parts of the windings being free from said metal layers.

5. An electric wound condenser of the flat type

comprising flat strip windings coiled upon themselves, a dielectric separating the conducting metal coatings of the condenser, said metal coatings of different potential vice versa projecting one on each front side of the condenser and at least three coherent layers of metal applied on the front sides electrically connected to the projecting edges of the coatings whereby the contact metal layers of the inner windings of the condenser are applied between the two bending points of the innermost winding and those of the outer windings on one or each rounded part of the front sides of the condenser and a metal wire conductor soldered to said applied metal layers, the inner bent parts of the windings being free from said metal layers, each conductor electrically connecting all of the applied metal layers on each side of said condenser, but being spaced from said windings.

6. An electric wound condenser of the flat type comprising flat strip windings of metal and insulating material coiled upon themselves to provide successive layers of metal and insulating material, alternate layers of metal being exposed at opposite sides, respectively, of said condenser, and a layer of metal applied to the edges of said windings at each side of said condenser to electrically connect metal layers of like polarity, the inner bent edges of said windings being free from said applied metal layers.
